N° 13713
S. Lovings design for a button
Patented Sep 25 1860

Des. 1313

Thomas Loring, of Blackwoodtown, N.J.
Letters Patent No. 1313, Sept. 25, 1860.

The schedule referred to in these Letters Patent, and making part of the same.

To all whom it may concern:

Be it known that Thomas Loring, of Blackwoodtown, Camden County, New Jersey, have invented or produced a new and original design for "Sod Grin"

Des. 1313

and I do hereby decline that the accompanying drawing with the following explanation of the same forms a full, clear, and exact description of the said design-

Fig. 1. of the drawing represents a side view of the said iron,

Fig. 2. a plan view-

Fig. 3. an end view- and

Fig. 4. a transverse section of the handle on the line 1. 2. Fig. 1.

A represents the base of the said iron, the said base being edged with a plain moulding a, and having a raised portion b, of the form represented in Fig. 2, for the reception of the handle B, which has a plain bead c, on the outside, as illustrated in the several views.

I claim the shape and configuration of the said iron represented in and by the accompanying drawing.

In testimony whereof, I have signed my name to this specification.

in the presence of the subscribing witnesses-

Exd. Affirmed
G. M. P. Henry, Lawyer,
Charles Hanson.
